PUMP MECHANISM

John W. Purvis, Detroit, Mich.

Application November 23, 1933, Serial No. 699,325

20 Claims. (Cl. 103—161)

My invention relates to improvements in variable stroke pumps in which pistons operate in conjunction with cylinders; and the objects of my improvement are, first, to provide a pump adapted to provide a variable displacement of the medium being pumped; second, to provide a pump with means for adjusting the position of its cylinders to accomplish a variable discharge of the medium being pumped; third, to provide a pump with a piston carrier member adapted to move as a unit relative to cylinder members to enable the pistons supported by the carrier member to effect a displacement of the medium being pumped; fourth, to provide a pump having a member provided with a plurality of cylinder portions connected with a distributing valve mounted internally relative to the cylinder portions; fifth, to provide a pump having an adjustable member adapted to move a valve and cylinder member transversely relative to the driving axis of the pump to vary the displacement of the pump; sixth, to provide a pump with a plurality of rotating cylinder members having their axes located out of alignment and connected by driving means permitting a uniform rate of motion of the rotating cylinder members; seventh, to provide a pump having an adjusting means adapted to optionally control the flow of the medium being pumped in opposite or reverse directions while operating or rotating in one continuous direction; eighth, to provide a pump operated by a driven shaft, with adjusting means adapted to permit the pump to be operated in a manner whereby the driven shaft will become a driving shaft; and ninth, to provide a pump with a single adjusting means adapted to control the displacement of the pump when constructed either as a single unit with four cylinders or as a double unit with eight cylinders.

I attain these objects by the mechanism illustrated in the accompanying drawings, in which—

Figure 1 is a plan view of the pump installed as a single unit in a housing shown without its cover portion; Fig. 2, a sectional view of the pump disclosed in Fig. 1, said sectional view being taken on the line 2—2, Fig. 1; Fig. 3, a plan view of the pump installed as a double unit in a housing shown without its cover portion; Fig. 4, a partial side view of the pump disclosed in Fig. 3, together with a partial vertical section through the pump, said vertical section being taken on the line 4—4, Fig. 3; Fig. 5, a plan view of the pistons, cylinders, and valve together with a partial plan view of the adjustable valve and the housing, the pump mechanism thereof being dis-

closed in a neutral position; Fig. 6, a sectional view of the pump mechanism disclosed in Fig. 5, said sectional view being taken on the line 6—6, Fig. 5; Fig. 7, a plan view of the pistons, cylinders, and valve, together with a partial plan view of the adjustable valve and the housing 1, the cylinders thereof being disclosed as having been shifted off center by the adjusting mechanism; Fig. 8, a sectional view of the pump mechanism disclosed in Fig. 7, said sectional view being taken on the line 8—8; Fig. 9, a sectional view through the pistons, cylinders and valve as disclosed in Fig. 8, the position of the cylinders having been displaced by the pump moving through an angle of thirty degrees from the position disclosed in Fig. 8; Fig. 10, a sectional view through the pump mechanism disclosed in Fig. 8, the position of the cylinders having been displaced by the pump moving through an angle of forty five degrees from the position disclosed in Fig. 8; Fig. 11, a sectional view through the pump mechanism disclosed in Fig. 8, the position of the cylinders having been displaced by the pump moving through an angle of ninety degrees from the position disclosed in Fig. 8; Fig. 12, an end view of a piston carrier together with the pistons assembled thereon; Fig. 13, a side view of the piston carrier and pistons disclosed in Fig. 12; Fig. 14, an end view of a valve member used in the pump when installed as a single unit; Fig. 15, a plan view of the valve member disclosed in Fig. 14; Fig. 16, an end view of one of the cylinder blocks; Fig. 17, a side view of the cylinder block disclosed in Fig. 16; Fig. 18, a side view of a driver member for the piston carrier and cylinder blocks; Fig. 19, an end view of the driver member disclosed in Fig. 18; Fig. 20, an end view of one of the cylinder blocks; Fig. 21, a side view of the cylinder block disclosed in Fig. 20; Fig. 22, an end view of a valve member used in the pump when installed as a double unit; Fig. 23, a plan view of the valve member disclosed in Fig. 22; Fig. 24, an isometric view of an alternative design of the piston carrier and cylinders, together with the driver member for the piston carrier and cylinders and also the valve adjusting mechanism before said parts are assembled together; Fig. 25, a plan view of a partial portion of the pump mechanism disclosing another alternate design of cylinders located on the center line of drive shaft instead of being offset; and Fig. 26, a sectional view through the pump mechanism disclosed in Fig. 25, said sectional view being taken on the line 26—26, Fig. 25.

Singular numerals refer to similar parts throughout the several views.

The housing 1 in Figs. 1 and 2 is provided with the bore 2 in which is mounted the bushing or bearing member 36, in which in turn is suitably mounted the valve member 3 which extends with 5 in the bore 4 of the cylinder block 5, the cylinder block 5 being provided with the keyway 6 which is adapted to receive the driving member 7 which is constructed of a sufficient width to enter therein and act as a key to drive the cylinder block 5. 10 The driving member 7 is provided with the bore 8 in which fits the drive shaft 9 and in which is mounted the key 10 for engaging the keyway 11 of the driving member 7. The driving member 7 may be provided with the extension boss or 15 hub 12 to provide sufficient stock for mounting the key 10 and to further provide additional length of the bore 8 to provide sufficient bearing on the drive shaft 9, the cylinder valve 3 being provided with the counterbore 13 to receive the hub 12.

The drive shaft 9 extends through and fits within the bore 14 of the valve member 3.

The piston carrier 15 is provided with the bore 16 which permits the drive shaft 80 to extend therethrough when a double unit installation is 25 provided, as in Figure 3.

The piston carrier 15 is provided with the body portion 17 in which are constructed the keyways or grooves 18 and 19, said keyways 18 and 19 being disposed on opposite sides of the body portion 17 relative to one another, said keyways 18 and 19 being further disposed at right angles relative to one another.

The driving member 7 is of sufficient width to 35 fit and operate as a driving key within the keyway 18. The cylinder block 20 is also provided with the key portion 21A which is adapted to fit the keyway 19 of the piston carrier 15.

The cylinder block 5 is provided with the cylinder bores 21 and 22 and the cylinder block 23 is provided with the cylinder bores 23 and 24.

The pistons or plunger members 25 and 26 are provided with the shank portions 27 which are suitably secured to and mounted in the bosses 28 of the piston carrier 15, the pistons 25 and 26 respectively and slidably operating in the cylinder bores 21 and 22 of the cylinder blocks 5. In a similar manner the shank portions 27 of the pistons or plunger members 29 and 30 are suitably secured in the bosses 28 of the piston carrier 15, the pistons 29 and 30 respectively and slidably operate in the cylinder bores 23 and 24 of the cylinder block 23. The cylinder block 23 is provided with the bore 31 in which is mounted one of the valve members 3A when a single unit 50 of the mechanism is used as disclosed in Figs. 1 and 2, said second valve member 3A being in turn suitably secured and mounted in the adjusting member 33 which is slidably mounted in the boss 34 of the housing 1, the second valve member 3A not requiring the counterbore 13 which is provided in the valve member 3.

The boss 34 is provided with the groove 35 in which the base of the adjusting member 33 slidably fits, the base of the adjusting member 33 being provided with the shoulder portion 36 which engages and is retained by the plate 37 which is secured by the screws 38. The adjusting member 33 is provided with the boss portion 39 having the bore 40 therethrough, in which the second valve member 3A is suitably mounted, the valve member 3A being adapted to be moved with the adjusting member 33 when it is slidably operated in the groove 35.

The valve members 3 and 3A are each provided

with the ports 41 and 42 which are machined around a portion of the periphery of the valve member 3, the ports 41 and 42 being separated by the blank spots or lands 43, the blank spots or lands 43 being located diametrically opposite one another to separate the ports 41 and 42.

The port 41 of the valve member 3 connects with the passage 44 which in turn connects with the passage 45, the passage 45 being connected with the connection or coupling portion 46 in 10 which is secured the intake pipe 47. The port 42 of the valve member 3 is connected to the passage 48 which in turn connects with the passage 49 which in turn connects with the connection or coupling member 50 in which is secured the outlet conduit or pipe 51, the connection or coupling members 46 and 50 being suitably secured in the ends of the valve member 3.

The second valve member 3A is similarly provided with the ports 41 and 42 which are respectively connected with the passages 44 and 48 which are in turn connected with the passages 45 and 49. The outer ends of the passages 45 and 49 in the second valve member 3A may be closed by the plugs 52. The adjusting member 33 is 20 provided with the shaft portions 53 and 54 which are slidably supported in the bosses 55 of the housing 1 and in the bosses 55A which form a portion of the bracket 59. The bosses 55 and 55A are respectively connected with the inlet 30 pipe 57 and the outlet pipe 58.

The bosses 55A are constructed in the bracket 59 which is removably mounted by means of the flange 60 which is secured to the housing 1 by the screws 61, the bracket 59 being provided with 35 a pilot portion which is supported in the bore 62 of the housing 1. The bracket member 59, being removably mounted in the housing 1, permits the adjusting member 33 to be moved sufficiently to one side to disengage the shaft portion 54 from 40 the bosses 55 of the housing 1, thus permitting the adjusting member 33 to be lifted jointly out through the top opening of the housing 1, it being understood of course that the inlet pipe or conduit pipe 57 will be disconnected in this disassembling operation.

In a similar manner the bushing or bracket member 36 is provided with a pilot portion for fitting within the bore 2 of the housing 1, the bushing 36 being further supported by the flange 50 63 which is secured to the housing 1 by the screws 64.

The shaft portions 53 and 54 of the adjusting member 33 are provided with passages 65 and 66, the passage 66 being closed at its outer end by 55 the plug 67. The passage 65 connects the port 41 in the second valve member 3A with the passage 68 which extends transversely through the shaft portion 53 to connect with the recess or undercut portion 69 which connects with the 60 passage 72 and thus with the inlet conduit or pipe 57. In a similar way the passage 66 connects the ports 42 in the valve member 3A with the passage 70 which extends transversely through the shaft portion 54 to connect with the recess 65 or undercut portion 71 in the shaft portion 54, the recess 71 further connecting with the passage 73 which in turn connects with the outlet pipe or conduit 58.

It is to be noted that the recess or undercut portion 69 and 71 will allow the adjusting member 33 and its shaft portions 53 and 54 to be adjustably moved longitudinally through its length or range of adjustment and at the same time 75

will always maintain connections respectively with the passages 12 and 13.

It is also to be noted that the ports 41 and 42, being extended around for the greater portion 5 of the periphery of the valve members 3 and 3A will always maintain connections respectively with the cylinder bores 21, 22, 23 or 24 of the cylinder blocks while rotating according to the cylinder block in which the valves 3 and 3A may be assembled.

It is to be noted that the cylinder bores 21 and 22 of the cylinder block 5 will be so machined that they will break through and be connected with the bore 4 of the cylinder block 5 at the 15 points 75 and 74. In a similar way the cylinder bores 23 and 24 of the cylinder block 20 will be so constructed that they will break through and connect with the bore 31 at the points 76 and 77.

Figures 12 and 13 disclose the manner in which 20 the pistons are assembled to the piston carrier 15. The pistons 25, 26, 29, and 30 are provided with the shank portions 27 as above mentioned, said shank portions fitting within the slots 78 of the portions 28 to permit the pistons to be slidably 25 mounted in the slots 78, the shank portions 27 being suitably threaded to engage the nuts 79 to secure them in place.

It is to be noted that the piston carrier 15 will thus be provided with two pistons on each side, 30 which are parallel to the keyway located on their respective sides of the piston carrier 15, the longitudinal centers of the pistons and the keyway, on each side of the piston carrier 15, being located at 90° of the longitudinal center of piston and 35 keyway on the opposite side of the piston carrier 15.

It is to be noted that after the pistons are placed in the cylinder blocks 5 and 20, the piston carrier 15 may then be slidably moved with respect to the driver or keyways, the piston carrier 40 15 then being adapted to slide either way on the keyways thereof to accomplish a change in the piston displacement of the pump mechanism.

It is to be noted that each cylinder block 5 45 and 20 will be provided with its own separate valve and each valve cooperates with two pistons only.

Figures 5 to 11 inclusive disclose the main operative parts of my pump mechanism when installed as a single unit,—that is, when used for 50 operating four pistons in four cylinders which designate a one unit installation.

Figures 5 and 6 disclose the single unit pump mechanism in its neutral position, the piston carrier 55 15 supporting two pistons which operate in the cylinder portions of the cylinder block 20 and two pistons which slidably operate in the cylinder portion of the cylinder block 5.

These Figs. 5 and 6 also disclose the valves 3 60 and 3A for the respective cylinder blocks, together with the driven member operatively mounted between the piston carrier 15 and the cylinder block 5, the drive shaft 9 extending through the valve 3 and into the drive member 7, 65 with which it is operatively connected, the valve member 3 forming a bearing for the drive shaft 9.

The valve member 3A is mounted and carried independently, as hereinabove described, on the 70 adjusting member 33 which, together with its shaft portions 53 and 54 may be suitably connected to and operated by manually or power operated means, such as cams, screws or hydraulic means, to provide the necessary mechanism for actuating the adjusting member 33.

75 It is to be noted that any amount or distance

that the adjusting member 33 and its shaft portions 53 and 54, together with its valve member 3A, is moved off the center of the drive shaft 9, either way, will accomplish a changing of displacement of the pistons carried by the piston carrier 15 and consequently accomplish a change in the flow of the medium or agent which is being pumped or displaced by the pump mechanism.

Figure 6 discloses the pump mechanism in a 10 neutral position in which the valves 3 and 3A coincide, or in other words are in alignment so that rotation of the piston carrier 15, together with its pistons when rotated, will produce a zero discharge or displacement.

Figures 7 and 8 disclose the cylinder member 20 as having been shifted off the center or in other words, misaligned, relative to the drive shaft 9, downwardly, as viewed in Figure 8. In moving the cylinder member 20 off the center, 20 as above described, and as disclosed more clearly in Figure 8, the key portion 21A remaining in a vertical position and with the shaft movement being in a horizontal direction, the pistons 29 and 30 which operate in the cylinder portions of 25 the cylinder member 20, did not change their displacement relative to their associated cylinder portions.

However, the piston carrier 15 will have been moved by the above described movement of the 30 cylinder member 20 so that the pistons 25 and 26, supported by the piston carrier 15 and operating in the cylinder portions of the cylinder member 5, will have changed their displacement to a full "out" stroke in the cylinder portions of the 35 cylinder member 5. If the above described offset movement of the cylinder member 20 had been made in an opposite direction as viewed in Figure 8, a reverse flow of the medium or agent being pumped, would have been the result in the cylinder portions of the cylinder member 5.

When the above mentioned adjusting movement downwardly, as viewed in Figure 8, is made, the piston carrier 15 will carry the pistons 29 and 30 with it to change their relations with their 45 associated pistons to the full "out" stroke in the vertical cylinder portions 23 while the piston 30 will have been moved to the upper portion of the cylinder portion 24 in the upper portion of the cylinder block 20.

It is to be further noted that the portion of the piston 29 as disclosed in Figure 8 corresponds to the end of the compression stroke whereas the piston 30 is disclosed as being at the end of its suction stroke or at the beginning of 55 its compression stroke.

It is also to be noted that if the above offset adjusting movement had been upwardly as viewed in Figure 8, instead of downwardly, a reverse flow of the agent or medium being pumped 60 would have resulted in the horizontal cylinder portions 23 and 24, or in other words, the relative portions of the pistons 29 and 30 would have been reversed relative to their associated cylinder portions 23 and 24.

It is to be further noted that in rotating the piston carrier 15 by the above mentioned operative mechanism, the key portions of the mechanism will operate on the principles of an Oldham coupling, the driving keys on the respective sides 70 of the piston carrier 15 being placed at right angles to each other so that the motion will be transmitted from the drive shaft 9 through its operatively associated parts at a uniform rate to the cylinder member 20 even when the drive shaft 75

9 is not in alignment therewith, thus permitting the operative motion of the above mentioned parts to drive the piston carrier 15 from the center line of one valve to the center line of the other valve with each 90° of rotation.

Figure 9 discloses the above described mechanism with a consequent displacement caused by a rotation from the position disclosed in Figure 8 through 30° angular motion. Similarly, Figure 10 discloses the valve mechanism as having been 5 rotatively advanced from its position at 30° in Figure 9 to 45° in Figure 10, whereas Figure 11 discloses the pump mechanism as having been 10 further rotatively advanced to a full 90° from the position as disclosed in Figure 8, or 45° beyond the portion disclosed in Figure 10.

It is to be understood that any intermediate 15 adjustment of the valve mechanism will reduce the flow or discharge of the medium or agent to be pumped from a maximum to zero, and an adjusting movement to the opposite side of the center of the drive shaft 9 will change the flow of the medium or agent being pumped to an opposite direction or reverse flow from zero to maximum capacity.

It is also to be noted that my pump mechanism 20 may be constructed with its valve member located in full offset and permanent positions and with no means for adjustment thereof, said mechanism thus being capable of being used as a driven unit from and connected with other similar units provided with adjustable means. With an adjustable unit such as disclosed in Figures 1 and 2 and operatively driven by power means such, 25 as an electric motor or similar power mechanism, at constant speed, said adjustable unit can be so positioned as to drive the above mentioned unit with its valves in permanent positions, at any variable speed, from zero to maximum speed in 30 either direction.

Figures 3 and 4 disclose my pump mechanism when installed as a double unit, each provided 35 with four pistons operatively mounted in their four associated cylinder portions to provide displacement and with the drive shaft 80 extending entirely through both of the units and the valve members 3 at each of its ends, the drive shaft 80 being connected with a valve member 3, cylinder member 5, drive member 7 and piston 40 carrier 20 in each group of pumping members located on opposite sides of the valve adjusting mechanism which is located at the transverse central portion of the housing 81 with a double unit installation, instead of adjacent the end of 45 the housing 1, as disclosed in Figure 2.

It is to be noted that whereas the piston carrier 15 may be constructed without a central bore in the single unit installations as disclosed in Figures 1 and 2, it is necessary to provide the piston 50 carrier with a central bore as disclosed in Figures 12 and 13 when my pump mechanism is constructed with a double unit installation to permit the piston carrier 15 to move transversely relative to the drive shaft 80 which extends all the 55 way through both of the pump units in order to provide driving means from one end of the drive shaft 80 to the other end of the double unit installation, the drive shaft 80 being disclosed in Figures 3 and 4 as being provided with the flange 60 coupling 86 which is suitably secured to the drive shaft 80 and adapted to permit driving connection with suitable driving means operatively connected with suitable power means used for driving the pump mechanism.

75 When my pump mechanism is used in the

double unit installations as disclosed in Figures 3 and 4 it is necessary to use the valve member 87 as disclosed in Figures 22 and 23.

The valve member 87 is mounted in the adjusting member 105 and is adapted to move therewith, the valve member 87 being provided with the ports 88 and 89 connecting respectively with the passages 90 and 91, the passages 90 and 91 connecting respectively with the passages 92 and 92A which extend longitudinally through the 10 valve member 87, the ends of said passages 92 and 92A being suitably plugged or closed. The ports 88 and 89 are thus connected with the cylinder portions of one of the cylinder blocks operatively mounted in one of the pumping units while the 15 ports 93 and 94 at the other end of the valve member 87 will connect the cylinder portions of the other of the cylinder blocks in the pump unit with the passages 92 and 92A by means of the passages 95 and 96. It will thus be noted that the 20 cylinder portions of both of the cylinder members oppositely disposed about the adjusting mechanism in the transverse central portion of the housing 81 of the double unit installations will be connected with the passages 97 and 98 which 25 are further connected with the passages 99 and 100 which connect with the passages 101 and 102 of the shaft portions 103 and 104 of the adjusting member 105 of the double unit installation as disclosed in Figures 3 and 4.

The passages 101 and 102 connect with the inlet conduit or pipe 106 and the outlet conduit or pipe 107 in a similar way to that described relative to the inlet and outlet pipes 57 and 58 in Figures 1 and 2.

It is also to be noted that the valve member 87 will be provided with the elongated slot 108 to permit the valve member 87 to be moved by the adjusting member 105 transversely relative to the drive shaft 80 which extends therethrough.

Figure 24 discloses an isometric view of various parts of my pump mechanism in alignment preparatory to final assembly in the operating unit. The cylinder blocks 109 and 110 thereof are made with a slightly different construction although 45 possessing similar operative principles on which the pump mechanisms, as above described, operate. In the construction as disclosed in Figure 24 the cylinder blocks 109 and 110, instead of being respectively provided with the keyway 6 50 and the key 21A, as disclosed relative to the cylinder blocks 5 and 20 are respectively provided with the extension or lug portions 111, 112, 113, and 114. The piston carrier 115 is provided with the slot or keyway 116 for engaging the lug 113 55 of the cylinder block 110, the piston carrier 115 being further provided with the slot or keyway 117 for engaging the lug 114 of the cylinder block 110.

In a similar way the cylinder block 109 is provided with the lugs 111 and 112 for engaging the slots 116, located on opposite sides and at right angles relative to the slots 116 and 117 of the piston carrier 115. The piston carrier 115 will be provided with a central opening 118, the wall surfaces of which are adapted to receive and engage the surfaces of the drive member 119 which thus acts as a key or drive member for transmitting the drive thrust to the piston carrier 115 which, when the cylinder block 113 is located in an adjusted or offset position relative to the axis of the driving member 119, will cause the piston carrier 115 and its supported pistons to operatively displace the medium or agent to be pumped in the cylinder portions of the cylinder blocks 109 and 75

110 in a similar manner to that as disclosed relative to the above described pump installations.

It is to be noted that the various parts of the construction as disclosed in Figure 24 have the same numerals as the similar parts which are disclosed in the preceding designs.

Figures 25 and 26 disclose another alternative construction in which the cylinder blocks 120 and 121 may be constructed if desired with their respective cylinder portions 122, 123, 124, and 125 located on the center of the drive shaft 126, the piston carrier 127 being provided with suitable key, extension, or lug portions for engaging suitable slots or keyways in the respective cylinder blocks 120 and 121. The piston carrier 127 will be provided with piston members which operate in a similar manner and on the same principles as in the above mentioned mechanisms, and the pistons can be placed at any intermediate point between the locations shown in Figs. 1, 3, 24, and 25.

The construction as disclosed in Figures 25 and 26 thus permit the center line of the pistons and their associated cylinder portions to be located on the center line of the drive shaft where desired and where the installation will permit a mechanism to be installed in a larger space, this construction requiring a slightly larger operating space for the revolving members thereof as the piston members of this construction must be placed on the outside of the valve members thereof, the cylinder portions being connected by suitable passages with the valve members thereof, in a similar way to that described in the above mechanisms. The construction as disclosed in Figures 25 and 26 also possesses the advantage of providing a balanced design in which the thrust of the various driving members is always exerted in line with the axis of the drive means, whereas in the above mentioned alternative constructions, the pistons will be offset with a consequent application of driving force at points removed from the center line of the driving means.

It is further to be understood that when it is desired to lock the adjusting means as above disclosed in permanent positions to permit the pump installation to be operated as a driven unit, the various housings may be provided with suitable holes or openings to permit the installation of locking means for engaging the adjusting means thereof or their attached shaft portions to provide the necessary means for locking the adjusting mechanism of my pump.

I claim:

1. In a pump mechanism, the combination of a housing, a valve member suitably mounted in said housing and provided with a pair of oppositely disposed ports extending peripherally thereon, said pair of ports being separated at their ends by a land on said valve member, said valve member being further provided with inlet and outlet passages connecting with said ports, a cylinder block revolvably mounted on said valve and provided with cylinder portions connecting with the ports of said valve member, an adjusting member movably mounted in said housing and provided with inlet and outlet passages extending therein, a second valve member suitably mounted in said adjusting member and adapted to move therewith, said second valve member being provided with a pair of oppositely disposed ports extending peripherally thereon, said pair of ports being separated at their ends by a land on said second valve member, said second valve member being further provided with inlet and

outlet passages connecting with said ports and with the inlet and outlet passages of said adjusting member, a second cylinder block revolvably mounted on said second valve member and adapted to move therewith to vary the displacement of the pump mechanism, said second valve member being provided with cylinder portions connecting with the ports of said second valve member, a piston carrier mounted on said first mentioned and said second cylinder blocks and adapted to drive said cylinder blocks, pistons suitably mounted in said piston carrier and adapted to operate in the cylinder portions of said cylinder blocks to displace a medium through the passages of said valve members and said adjusting member, a drive shaft suitably mounted and extending through said first mentioned valve member, said drive shaft being operatively connected with said piston carrier, and means for conducting said medium to and from the passages of said first and said second mentioned valve and said adjusting member.

2. In a pump mechanism, the combination of a pair of cylinder members revolvably mounted and each provided with a pair of cylinder chambers extending longitudinally in parallel planes oppositely disposed about the axis of said cylinder member, piston members adapted for movement in said pair of cylinder chambers to displace a medium, means connecting said piston members and moving therewith, said means being reciprocatingly mounted on said cylinder members, and means for adjusting the position of said pair of cylinder members relative to said piston members to vary the amount of said medium being displaced.

3. In a pump mechanism, the combination of a valve member, a cylinder member revolvably mounted on said valve member and provided with a pair of cylinder chambers extending longitudinally in parallel planes oppositely disposed about the axis of said cylinder member, piston members adapted for movement in said cylinder chambers to displace a medium from said cylinder member to said valve member, means operatively connecting said piston members to cause reciprocating movement thereof, said means being mounted to reciprocate in a plane extending transversely through the axis of said cylinder member, and means for adjusting the position of said valve and said cylinder members relative to said piston members to vary the displacement of said piston members.

4. In a pump mechanism, the combination of a pair of rotatably mounted cylinder members, a piston carrier mounted on said cylinder members and adapted to rotate therewith, said piston carrier being provided with a pair of pistons movably mounted in each of said cylinder members, said piston carrier having a hub portion extending between and spacing said cylinder members axially, means for driving said piston carrier, and means for displacing one of said cylinder members relative to the axis of the other of said cylinder members to change the displacement of the pump mechanism.

5. In a pump mechanism, the combination of a carrier member provided with a body portion having a pair of key portions each extending substantially at right angles with the other, said body portion being further provided with a plurality of oppositely disposed pairs of bosses extending therefrom, a pair of valve members, a pair of cylinder members rotatably mounted on

said pair of valve members and each slidably connected with one of said key portions of said carrier member, said cylinder members being adapted to rotate with their axes out of alignment, 5 said cylinder members being provided with cylinder spaces connected with said valve members, a pair of piston members suitably mounted in each pair of said oppositely disposed bosses of said carrier member and adapted to move in said cylinder spaces of said cylinder members to displace a medium being pumped, each of said pair of piston members extending longitudinally in planes located parallel with one of said key portions of said carrier member, and 10 means for driving said carrier member.

6. In a pump mechanism, the combination of a driving member provided with pairs of pistons, said driving member being revolvably mounted, a pair of cylinder members revolvably driven by 15 said driving member and each provided with cylinder spaces adapted to receive a pair of said pistons, said cylinder members being oppositely disposed about and axially spaced by said driving member, and means for adjusting the position of one of said cylinder members relative to said driving member to vary the displacement of the pumping mechanism.

7. In a pump mechanism, the combination of a pair of cylinder members revolvably mounted 20 and each provided with a pair of cylinder spaces extending longitudinally at right angles to the axes of said cylinder members, coupling means for driving said cylinder members, said coupling means being adapted to rotate, said coupling 25 means being provided with pistons extending into said cylinder spaces to displace a medium being pumped, said coupling means being provided with a hub portion extending between and spacing said cylinder members, and means for driving 30 said coupling means.

8. In a pump mechanism, the combination of a housing member, bracket members mounted on said housing and each provided with a bore, a cylindrical member mounted in the bore of each 40 of said bracket members and provided with passages, a cylinder block rotatably mounted on one of said cylindrical members and provided with cylinder spaces oppositely disposed about the axis of said cylinder block, a second cylinder block 45 rotatably mounted on the other of said cylindrical members and provided with cylinder spaces oppositely disposed about the axis of said second cylinder block, said cylinder spaces of each of said cylinder blocks connecting with the passages 50 of one of said cylindrical members, a piston carrier slidably mounted on said cylinder blocks and provided with key mechanisms engaging said cylinder blocks, said key mechanisms extending at right angles with one another, pistons mounted 55 in said piston carrier and entering the cylinder spaces of said cylinder blocks, the pistons in the cylinder spaces of each cylinder block extending longitudinally in parallel planes with the key mechanism of said cylinder block, and means for 60 rotating said cylinder blocks and said piston carrier.

9. In a pump mechanism, the combination of a pair of valve members mounted and provided with passages for conducting a medium to be 65 pumped, a pair of cylinder members rotatably mounted on said valve members and provided with bores connecting with the passages of said valve members, said bores of each cylinder member extending longitudinally in parallel planes located 70 on opposite sides of the axis of said cylinder

member, piston members extending in said bores of said cylinder members, a carrier member fixedly connected to and supporting said piston members, means operatively connecting each of the opposite sides of said carrier member with one of said cylinder members to enable said cylinder members and said carrier to be rotated together, said means comprising a body portion having a pair of key portions extending substantially at right angles with one another and each engaging one of said cylinder members, said means permitting said carrier to be slidably moved in a pair of planes extending at right angles with one another and parallel with said pistons, and means for driving one of said cylinder members with 15 a rotary motion, said last mentioned means driving said carrier and the other of said cylinder members through said first mentioned means.

10. In a pump mechanism, the combination of rotatably mounted cylinder members, a carrier 20 member solely connected with said cylinder members and extending between and spacing said rotatably mounted cylinder members, the connection with said cylinder members enabling said carrier to be reciprocated on said cylinder members in planes extending at right angles to one another, pistons solely connected to said carrier member and extending longitudinally in said cylinder members in planes located parallel with said planes of reciprocating movement of said 25 carrier member, said pistons being solely actuated in reciprocating movements by said carried member, means for driving said cylinder members and said carrier member, and means for conducting a medium, being pumped, to and from said cylinder members.

11. In a pump mechanism, the combination of a valve member suitably mounted and provided with conduit passages together with a bore, a cylinder member provided with bores connecting 40 with the conduit passages of said valve member, said cylinder member being provided with a keyway extending transversely relative to its axis, a carrier member provided with piston members movably mounted in the bores of said cylinder 45 member, said carrier member being provided with a keyway extending parallel with the keyway of said cylinder member, said carrier member being further provided with a keyway extending substantially at right angles to its first mentioned 50 keyway, a second valve member suitably mounted and provided with conduit passages, a second cylinder member suitably mounted on said second valve member and provided with a key engaging a keyway of said carrier member, said second 55 cylinder being provided with bores engaged by said pistons of said carrier member, said bores of said second cylinder member being connected with the conduit passages of said second valve member, a driving member engaging the parallel 60 keyways of said first mentioned cylinder member and said carrier member, and a shaft member revolvably mounted in the bore of said first mentioned valve member, said shaft member being operatively connected with said driving member. 65

12. In a pump mechanism, the combination of a housing provided with a pair of oppositely disposed bosses provided with bores therethrough together with conduit passages connecting with each of said bores, said bosses being in alignment, an 70 adjusting member provided with shaft portions mounted in the bores of the bosses of said housing, said adjusting member being adapted to be slidably moved in said bores, said adjusting member being provided with a bore extending trans- 75

- versely therein, said adjusting member being provided with passages connecting its bore with the conduit passages of the bosses of said housing, a valve member mounted in the bore of said adjusting member and provided with conduit passages connecting with said conduit passages of said adjusting member, said valve member having its axis located in alignment with the axis of said adjustment member, a cylinder means rotatably mounted on said valve member and provided with bores, a piston carrier movably mounted on said cylinder means, piston members movably mounted in the bores of said cylinder member, said piston members being fixedly secured to said piston carrier, and means for reciprocating said pistons, and said piston carrier in planes extending at right angles to each other, each of said planes extending parallel with the axis of a pair of said pistons.
13. In a pump mechanism, the combination of an adjusting member movably mounted and adapted for movement in a transverse direction only relative to the axis of the pump mechanism, a valve member suitably mounted in said adjusting member and provided with extension portions at each side of said adjusting member, said valve member being provided with conduit passages, a cylinder member rotatably mounted on each of the extension portions of said valve member and provided with bores connecting with the conduit passages of said valve member, a piston carrier movably supported on each of said cylinder members, piston members extending in the bores of said cylinder members, the piston members in each of said cylinder members extending longitudinally in parallel planes, said piston members being fixedly secured to said piston carrier, and means for revolving said piston carrier to reciprocate said piston members in each of said cylinder members in planes parallel with the axes of said piston members in each of said cylinder members.
14. In a pump mechanism, the combination of a pair of cylinder members rotatably mounted and provided with bores extending transversely relative to their axes, a carrier member suitably mounted to rotate with said cylinder members, said carrier member being provided with a body portion spacing said cylinder members and having lug portions extending adjacent the open ends of said bores of said cylinder members, said carrier member being slidably connected with said cylinder members to prevent movement of said carrier member relative to said cylinder member except in transverse planes relative to the axis of said cylinder members and extending at right angles to one another, piston members suitably secured in the lug portions of said carrier member and extending within the bores of said cylinder members, and means rotating said piston carrier and said cylinder members causing a reciprocating motion between said cylinders and said piston members to displace the medium being pumped, said piston members moving longitudinally in parallel planes in each of said cylinder members.
15. In a pump mechanism, the combination of a pair of cylinder members each provided with a pair of cylinder spaces oppositely disposed relative to the axis thereof, a piston carrier supported on said cylinder members and slidably connected therewith, to permit movement, relative to the axes of said cylinder members, only in planes extending at right angles to one another and to the axes of said cylinder mem-
- bers, pistons mounted in said piston carrier and engaging said cylinder spaces, said pistons, in each of said cylinder members, extending longitudinally in planes parallel to each other and to the slidable connection between said cylinder members and said piston carrier, valve members supporting said cylinder members and provided with passages connecting with said cylinder spaces, and means for driving said piston carrier and said cylinder members with a revolving movement to reciprocate said pistons in said cylinder spaces.
16. In a pump mechanism, the combination of a pair of valve members, cylinder members revolvably mounted on said valve members and adapted to guide the medium being pumped into said valve members, a piston carrier movably supported on said cylinder members and extending therebetween to space said cylinder members longitudinally, said piston carrier being supported in eccentric relationship to said cylinder members, pistons mounted in said piston carrier and extending within said cylinder members, and means for revolving said cylinder members and said piston carrier to reciprocate said pistons in said cylinder members.
17. In a pump mechanism, the combination of a pair of valve members provided with passages, a pair of cylinder members revolvably mounted on said valve members and provided with cylinder spaces connecting with the passages of said valve members, means supported on said cylinder members and operatively keyed to said cylinder members to permit movement of said means only in planes extending at right angles to one another and to the axes of said cylinder members, said means being provided with pistons extending into said cylinder spaces of said cylinder members, and means for revolving said means.
18. In a pump mechanism, the combination of a pair of cylinder members revolvably mounted, carrier means between said cylinder members and slidably connected therewith by key portions extending at right angles with one another and with the axis of said carrier means, pistons in said carrier means and engaging said cylinder members, means for guiding a medium into and out of said cylinder members, means for displacing said carrier means in a transverse direction relative to the axis of one only of said cylinder members, and means for revolving said carrier means and said cylinder members.
19. In a pump mechanism, the combination of a pair of cylinder members revolvably mounted, means supporting one of said pair of cylinder members and adapted for movement in a plane extending transversely relative to and through the axis of the other of said cylinder member, a carrier member slidably mounted between and on said cylinder members and adapted to revolve therewith, pistons in said carrier member and engaging said cylinder members, valve means suitably mounted and connected with said cylinder members for guiding a medium to and from said cylinder members, and means for revolving said carrier and said cylinder members to reciprocate said pistons in said cylinder members.
20. In a pump mechanism, the combination of a housing provided with a groove and bores extending parallel with said groove, an adjusting member slidably mounted in said bores and provided with a base portion sliding in said groove, a valve member in said adjusting member and having its axis extending transversely to and in a plane extending through the axis of said bores

of said housing, a second valve member fixedly mounted in said housing and having its axis located in a plane extending through the axis of said first mentioned valve member, a pair of cylinder members revolvably mounted on said valve members, a carrier member slidably mount-

ed on said cylinder members and provided with pistons extending within said cylinder members, means for revolving said carrier and said cylinder members, and conduit means connected with said valve members.

JOHN W. PURVIS.
